United States Patent Office.

WILLIAM KLEMM AND ROBERT DITTRICH, OF PITTSBURG, PENNSYLVANIA.

Letters Patent No. 74,834, dated February 25, 1868.

IMPROVED BOLT-MAKING MACHINE.

The Schedule referred to in these Letters Patent and making part of the same.

Be it known that we, WILLIAM KLEMM and ROBERT DITTRICH, both of Pittsburg, in the county of Allegheny, and State of Pennsylvania, have invented a new and useful Machine for Heading Bolts and Rivets; and we do hereby declare that the following is a full, clear, and exact description of the construction and operation of the same, reference being had to the annexed drawings, making a part of this specification, in which—

Figure 1 is a perspective view of our machine.

A is the bed-plate of the machine; B are the legs or supports for the bed-plate A; C is the stationary gripping-die; D is the movable gripping-die; E is the movable head which carries the header W; F is an eccentric yoke enclosing the eccentric G; G is an eccentric on the shaft M, working the strap F; H is a key working in the eccentric-yoke F; I is a key working in the eccentric-strap L; K is an eccentric on the shaft M; L is an eccentric-strap on the eccentric K; M is the shaft carrying the eccentrics K and G, and pulley R; N is a shaft which carries the levers b, d, and f; O is a treadle vibrating on the pin P; P is the pin which supports the treadle O; Q is a counterbalance-weight attached to the treadle O; R is the driving-pulley on the shaft M; S is a link vibrating on the centre at U; T is a link connected with S, and moving the die D; W is the heading-tool in the sliding head E; X is the half circular groove in D to hold the bolt-blanks; a is a link connecting the key H with the lever b; b is a lever on the shaft N, supporting link a and key H; c is a link connecting the key I with the lever d; d is a lever on the shaft N, supporting the link c and key I; e is a link connecting the treadle O with the lever f; f is a lever on the shaft N, connected with treadle O by e; g is an opening in the bed-plate A, through which the blanks are passed into the gripping-dies C and D.

To enable others skilled in the art to make and use our invention, we will proceed to describe its construction and operation.

The blanks for manufacture into bolts or rivets, as desired, (having been cut to the desired lengths,) are passed through the hole g, and between the gripping-dies C and D, until the end comes in contact with the heading-die W. The foot is then placed upon the treadle O, the treadle depressed until the keys H and I come in contact with the faces of the eccentrics G and K, (as shown in the accompanying drawing.) The shaft M and eccentrics G and K having been put in motion by means of a belt upon the pulley R, the eccentrics G and H come in contact with the keys H and I, which forces forward the eccentric-straps F and L. The eccentric, G, being set on the shaft M, forward of the eccentric, K, will cause the strap F to move in advance of the strap L. The moving forward of the strap F causes the toggle-joint, composed of the links S and T, to straighten out, and this toggle vibrating upon a stationary point at V, and being connected with the gripping-die D at the point V, the die D will be brought forward until it grips between itself and the die C the bolt-blank, which was previously inserted through the opening g. The eccentric, K, then comes forward, and gives a forward motion to the slide E and heading-die W. This brings the heading-die in contact with the bolt-blank, and compresses the metal of the latter into the cavity in the die, made in the form of the desired head. The heading cavity may be in either the heading-die, the gripping-dies, or in both. After the bolt is thus formed, the foot is removed from the treadle O, the counter-weight g causes the treadle to rise, and through the connections e f N a b c d, the keys H and I are lifted from their position, above the line of motion of the eccentrics G and K, and the shaft and eccentrics can then continue to revolve without moving forward the straps F and L, until the bolt or rivet just made has been removed, and another blank inserted ready to be headed, and the treadle O once more depressed. When the strap F has been brought forward by the eccentric, G, until the gripping-dies C and D are pressing tightly upon the blank, the toggle-joint, composed of the links S and T, assumes a straight line, and the pressure of the gripping-dies then comes directly upon the bed of the machine at U, without pressing upon any of the working parts of the machine. The working parts are thus kept in better order, and with less wear than when the eccentric operates directly upon the gripping-dies, as is usually the case.

What we claim as our invention, and desire to secure by Letters Patent of the United States, is—

The keys H and I or their equivalent, arranged in relation to the other parts of the machine, and operated substantially as described, and for the purpose set forth.
